UNITED STATES PATENT OFFICE.

PERCY MILES SNIDER, OF DETROIT, MICHIGAN, ASSIGNOR OF ONE-HALF TO FRED E. TALLMADGE, OF DETROIT, MICHIGAN.

GAS-MIXER.

1,279,771.

Specification of Letters Patent. Patented Sept. 24, 1918.

Continuation of application Serial No. 122,347, filed September 27, 1916. This application filed February 11, 1918. Serial No. 216,517.

To all whom it may concern:

Be it known that I, Percy Miles Snider, a citizen of the United States, and residing at Detroit, in the county of Wayne and State of Michigan, have invented a new and Improved Gas-Mixer, of which the following is a specification.

This invention is embodied in a device which intimately mixes the gases and air that pass from city street gas mains to the stoves, ranges, furnaces or heaters where they are to be burned, and its object is to produce a mixer that will be simple and effective.

15 This invention consists of a nozzle adapted to give a whirling and intermixing movement to the gases that pass through it, which nozzle is introduced into the conduit that conveys the gases to the place of combustion. It further consists in fitting a disk of fine wire webbing across the intake end of the nozzle to break up the streams of gases passing to the nozzle.

20 This application is in part a continuation 25 of my former application No. 122,347, filed September 27, 1916.

In the accompanying drawing, Figure 1 is an elevation of a gas meter, gas stove and the pipe connecting them. Fig. 2 is a 30 longitudinal section of a pipe union with my improved mixer in position. Fig. 3 is a side elevation and Figs. 4 and 5 the two end elevations of this mixer. Fig. 6 is a longitudinal section of a pipe with a slightly 35 modified form of mixer in position.

Similar reference characters refer to like parts throughout the several views.

Fig. 1 of the drawing shows conventionally a gas stove 1, a gas meter 2 and a pipe 3 connecting them. It will be understood that the stove represents any desired mechanism wherein gas may be burned. A union 4 of well known construction is interposed between the gas measuring and gas 40 suming devices. This union consists of the usual ends 5 and 6 screwed onto the ends of the pipe 3, and a nut 7 that connects the ends. The adjacent faces of the ends 5

and 6 are flat and between them this novel gas mixing device is mounted.

As shown in the drawing, this device consists of a cylindrical body 9 having a radial flange 10 at one end, the opposite end being tapered to constitute a nozzle 11 and this nozzle being formed with substantially spiral internal grooves 12. A disk 14 of woven wire may be mounted within the cylindrical body 9. A washer 15 of rubber, leather or other desirable material may be employed to secure this mixing device in position.

When the mixer is to be positioned intermediate the ends of a length of pipe 17, the flange 10 will be omitted, as shown in Fig. 6, in which case the body 9 of the mixer 65 should snugly fit the interior surface of the pipe in order to hold it in position.

Ordinary city gas is not a single permanent gas but a mixture of gases and usually carries a considerable percentage of 70 air. The probable action of this mixing device is to give to these mixed gases a whirling motion, intimately mixing them so that they will be in perfect condition to burn with the hottest possible flame. The 75 screen 14 breaks up these gases as they flow through the mixer. The exact operation of this device is not fully understood, but it has been found by actual practice that the amount of gas required to heat 80 equal quantities of water is much less when this mixer is used than without it.

I claim:

1. In combination with a pipe for conducting gas to a burner, a gas mixer 85 mounted in said pipe and comprising a cylindrical body through which the gas flows, the discharge end of the body being tapered and formed with substantially spiral channels on the inner side of the tapering 90 end to cause the gas passing through the mixer to revolve and be thoroughly mixed, and a screen within the body to break up the stream of gas before it.

2. In combination with a pipe for conducting gas to a burner, a union in said

pipe, a gas mixer mounted in said union and comprising a cylindrical body through which the gas flows and having an outwardly extending radial flange at the receiving end adapted to be gripped between two parts of the union, the opposite end of the body being tapered and formed with

substantially spiral channels on the inner side of the tapering end to cause the gas passing through the mixer to revolve and be thoroughly mixed, and a screen within the body to break up the stream of gas before it reaches said spiral channels.

PERCY MILES SNIDER.
